Patented Oct. 9, 1928.

UNITED STATES PATENT OFFICE.

WILLIAM G. MANSUY, OF DETROIT, MICHIGAN.

PLASTIC MATERIAL FORMING AND SMOOTHING DEVICE.

Application filed February 26, 1927. Serial No. 171,097.

My invention relates to a new and useful improvement in a plastic material smoothing and forming device adapted for use particularly in smoothing cement and terrazzo floors and the like, which are made from a plastic material, and is particularly adapted for use in smoothing these floors, in conjunction with which there is formed a wall board or base from the plastic material.

It is an object of the present invention to provide a device whereby the floor and wall or base board may be easily and quickly smoothed and formed, and whereby a uniform planal surface on the outside of the wall or base board may be provided.

Another object of the invention is, in addition to the provision of a device where a saving of labor will be effected, the provision of a device for this purpose whereby a saving of material may also be effected.

Another object of the invention is the provision of a device of this kind which will be economical of manufacture, durable of structure, easy to operate and highly efficient in use.

Other objects will appear hereinafter.

The invention consists in the combination and arrangement of parts hereinafter described and claimed.

The invention will be best understood by a reference to the accompanying drawings which form a part of this specification and in which,

Fig. 1 is a sectional view taken on line 1—1 of Fig. 4.

Fig. 2 is a front elevational view of the invention.

Fig. 3 is a top plan view of the invention.

Fig. 4 is a fragmentary sectional view taken on substantially line 4—4 of Fig. 1.

As shown in the drawings, the invention is adapted for use in smoothing the plastic material 9 which forms the floor of a room such as a bath room or the like, in which there is a base or wall board 10 formed from the same plastic material and integral with the floor 9.

In the invention I have provided a frame comprising the side rails 11 and 12, preferably made from angle iron, each of which is angularly turned to provide the laterally projecting portion 13 at its upper end and angularly turned to provide, adjacent its lower end, the angularly turned portion 14, which is again angularly turned as at 15 to extend parallel to the main body. These

angle irons are connected at their upper end by a cross beam 16 which is also preferably an angle iron, and which has its ends 17 and 18 flared for purposes which will appear as the description proceeds. The angularly turned portions 15 of these side rails are connected by the cross beam 19, projecting outwardly from which are the guide members 20 and 21 which, when the device is in use, engages the face of the screed strip 22, the angle iron 19 resting on the upper face of this screed strip 22. Bolted, or otherwise suitably secured to each of these side rails at the lower end, is a trowel block 23, secured to the undersurface of which and extending around the rearward side thereof, is a metallic plate 24 which forms a trowel on the block. As shown in Fig. 1, the rearward side of the block is provided with the rearwardly projecting nose 25.

The device when constructed as described, may be utilized for levelling the floor 9 and forming the base board 10, thus eliminating the necessity of handwork on this particular construction. The plastic material is deposited on the support which is intended to support the floor 9 and the device placed in position, as shown in Fig. 1, so as to press enough of the plastic material between the trowel forming plate and the wall 26 of the room. The guide strips 20 and 21 will engage the face of the screed strip 22, as shown in Fig. 1, the angle iron 19 resting upon the upper surface of this screed strip. The angle iron 16 engages the wall of the room and the device moved laterally so as to smooth the plastic material forming the floor 9 and to form and smooth the plastic material forming the base or wall board 10. Ordinarily in operation the nose 25 will not be in engagement with the wall 26, as the guide strips 20 must be retained in engagement with the face of the screed strip. The screed strip sill therefore determine the plane of the wall and the base board 10, this being desirable on account of the depressions and rises in the wall 26. As the angle iron 16 is drawn over the surface of the wall 26, the flared ends 17 and 18 will permit an easy and ready passage of this angle iron along the wall, particularly where a projection may be present on the wall. The frame therefore serves as a trowel frame and the trowel forming plates carried on the block will serve as trowels for leveling the surfaces operated upon. Since the nose 25 does not engage the wall 26, there

will be a slight amount of the plastic material projecting upwardly from the upper surface 27 of this base board which may be easily and quickly removed by a workman 5 using his hand trowel.

In this way, I have provided a device which is quite durable and simple in its structure, which may be operated by unskilled labor, and produced as finished a job as a skilled 10 artisan now customarily performs when working by hand. A considerable saving in labor results. The finish of the job is far superior to the average job as now done, so that considerable advantage results from the 15 use of this device.

If desired, this trowel, of course, may be mounted centrally of the frame or at any other position, but it has been proven from experience that the mounting of the trowel 20 at each end of the frame permits the use of the device for smoothing the plastic material close against the end walls of the room and particularly in corners and the like, thus reducing the hand operation to a minimum.

25 While I have illustrated and described the preferred form of structure, I do not wish to limit myself to the precise details of structure shown, but desire to avail myself of such variations and modifications as come within 30 the scope of the appended claims.

Having thus described my invention on what I claim as new and desire to secure by Letters Patent is:

35 1. A device of the class described comprising: a frame having side rails; a block mounted on each of said side rails; an L shaped trowel forming member mounted on each of said blocks; a guide member carried by said frame; and a nose on the rearward 40 side of said block projecting outwardly from a vertically extending portion of said trowel forming member.

45 2. A device of the class described, comprising: a frame; a horizontally extending trowel forming member carried by said frame; a vertically extending trowel forming member carried by said frame, said frame projecting beyond the engaging surface of said verti-

cally extending trowel forming member above the same and adapted for engaging a 50 wall of a room with which used; and a guide member carried by said frame adapted for engaging an abutment and limiting withdrawal of said vertically extending trowel forming member from said wall beyond a pre- 55 determined distance.

3. A device of the class described, comprising: a frame; a vertically extending trowel forming member carried by said frame; a horizontally extending trowel forming mem- 60 ber carried by said frame; and a smoothing member carried by said frame and projecting outwardly beyond the engaging face of said vertically extending trowel forming member.

4. A device of the class described, comprising: a frame; a vertically extending trowel forming member carried by said frame; a horizontally extending trowel forming member carried by said frame; a smoothing member carried by said frame and projecting outwardly beyond the engaging face of said vertically extending trowel forming mem- 70 ber; and a guide member carried by the outer side of said frame for engaging an abutment and limiting withdrawal of said vertically 75 extending trowel forming member from said frame beyond a predetermined distance.

5. A device of the class described, comprising: a frame having a pair of L-shaped members, the ends of each of the legs being angularly outwardly turned; a cross beam connecting the angularly turned upper ends of said frame; a cross beam connecting the angularly turned lower ends of said frame; a guide strip carried by said second mentioned cross beam and projecting downwardly below the lower surface of said frame; a pair of blocks secured to said frame in spaced relation; a trowel member on the lower end inner face of each of said blocks; a projection on the inner face of each of said blocks extending beyond the upper edge of said trowel forming member on said face.

In testimony whereof I have signed the foregoing specification.

WILLIAM G. MANSUY.
